UNITED STATES PATENT OFFICE.

ROBERT S. RODIE, OF JERSEY CITY, NEW JERSEY.

STEAM-BOILER.

SPECIFICATION forming part of Letters Patent No. 406,235, dated July 2, 1889.

Application filed March 30, 1889. Serial No. 305,368. (No model.)

To all whom it may concern:

Be it known that I, ROBERT S. RODIE, of Jersey City, in the county of Hudson and State of New Jersey, have invented a new and Improved Steam-Boiler, of which the following is a full, clear, and exact description.

My invention relates to steam-boilers, more especially designed for steamships or boats, but serviceable anywhere for producing motive power.

The invention has for its object to provide a compact, easily-constructed, and comparatively inexpensive boiler of large steaming capacity, and having great strength to promote safety against explosion.

The invention consists in certain novel features of construction and combinations of parts of the steam-boiler, all as hereinafter described and claimed.

Reference is to be had to the accompanying drawings, forming a part of this specification, in which similar letters of reference indicate corresponding parts in all the figures.

Figure 1 is a vertical longitudinal section of my improved steam-boiler, taken on the line 1 1 in Fig. 2, the steam-dome and the back connection or uptake being partly broken away and the grate-bars removed.

Fig. 2 is a plan view of the boiler in horizontal section on the line 2 2 in Fig. 1 and partly broken away. Fig. 3 is a vertical transverse section taken on the line 3 3 in Fig. 2; and Fig. 4 is a side elevation of the boiler, drawn to a smaller scale, and with the man-hole covers and furnace-door removed.

The shell of the boiler is made with two cylindrical or rounded sections A B, which are joined diagonally at a, so as to have the general form of an ordinary pipe-elbow.

Above the fire-box section A and the front end portion of the section B is fixed the steam-dome C, which communicates by an opening b in the section B with the steam-space of the boiler, and has a man-hole c, which will have a suitable cover. Behind

and above the rear boiler-section B and the steam-dome C is arranged the sheet-metal casing D, which is the uptake or back connection through which the products of combustion pass to a flue or stack E, with which the uptake communicates. The uptake has

a suitable door d, giving access to the rear fire-tubes of the boiler.

The boiler fire-box F, in which the fuel-receiving grate G is placed, is located at the lower rounded end of the front section A, and is bounded by a crown and tube sheet f and an annular side wall f', the latter being stayed to the outer shell or plate of this front section of the boiler by suitable bolts f². Above and partly in rear of the fire-box is formed within the boiler-shell an upper combustion-chamber H, bounded by a lower or bottom wall h, which, with the fire-box crown-sheet f, gives support to the front vertically-ranging series of fire-tubes I, which establish communication between the fire-box F and combustion-chamber H. The upper wall or crown-sheet h' of the combustion-chamber is stayed to the outer laterally-rounded shell of the boiler-section B by suitable stay-bolts J. The rear wall h² of the chamber H forms, with the rear end sheet b' of the boiler-shell section B, the support for the rear horizontal longitudinally-ranging series of fire-tubes K and flues L, which establish communication between the combustion-chamber and the uptake. Another wall of the combustion-chamber is formed of a sheet or plate h³, which extends across the boiler-section B, and for the most part inclines downward and rearward from its joint with the plate h to a point preferably a little below the top of the fire-box F, where it is bent rearward to connect with the lower edge of the tube-sheet h², into which the forward ends of the tubes and flues K L are expanded. A bottom plate m, which is rounded to conform to the general shape of the boiler-section B, and is stayed thereto by suitable bolts m', forms below the fire-tubes and flues K L a water-space M', which communicates with the general water-space M around the fire-box, and between it and the combustion-chamber around the fire-tubes L, and above and around the rear fire-tubes and the combustion-chambers.

I use stay-bolts N between the fire-box and combustion-chamber plates f h and stay-bolts O between the plates f h³ to stiffen them. Stays P are also provided between the top of the boiler-shell section B and its back plate b' for the sole purpose of stiffening this plate at

its upper part, its lower part being stayed by the fire tubes and flues K L, which also stay the rear plate h^2 of the combustion-chamber. The stays J N O P are indicated mainly by 5 dotted lines in the drawings.

A flue R is fitted to and between the plates h' and h^3 of the combustion-chamber H and traverses this chamber vertically at its transverse center and toward its rear part and a 10 little distance in front of the fire-tubes and flues K L, so as not to obstruct passage of hot products from the chamber to these fire-tubes and flues. This flue R gives free passage to a man entering at the steam-dome 15 hole c and passing through the shell-opening b between the upper and lower portions of the steam and water space M of the boiler, thus giving him access to the interior surfaces of the water-space to clear them of scale 20 and sedimentary deposits, and the flue R serves also as a water-circulation tube, through which a constant active upward circulation of water is maintained in the boiler, and the flue also materially increases the fire-surface 25 and assures quick and steady steaming of the boiler with economy of fuel.

The products of combustion from the fuel on the fire-grate G pass from the fire-box F through the fire-tubes I into the combustion-chamber H, whence they pass around the flue or tube R into and through the fire-tubes and flues K L to the uptake or back connection D, and thence over the boiler-shell to the stack.

35 While I specially claim as my invention certain features of construction of the interior of the boiler, as hereinafter set forth, I make special mention of and claim to the main boiler-shell made in two cylindrical or 40 rounded sections joined diagonally in elbow form, which makes the entire shell self-bracing around the sides, thus enabling me to dispense with many stay-bolts used to brace the shells of boilers otherwise formed. The 45 stay-bolts used in the boiler are employed only to brace its rear end plate and the walls of the fire-box and combustion-chamber to enable them to resist the outward or bursting pressure in the water and steam space of the 50 boiler, as will readily be understood.

Having thus described my invention, what I claim as new, and desire to secure by Letters Patent, is—

1. A boiler made in two cylindrical or 55 rounded sections connected by an elbow-joint to produce a self-bracing shell, and provided on the upper horizontal section with a steam-dome, substantially as herein set forth.

2. A boiler made in two cylindrical or

rounded sections connected by an elbow-joint 60 to produce a self-bracing shell, and an uptake or back connection extending at the rear and top of the shell, substantially as herein set forth.

3. A boiler made in two cylindrical or 65 rounded sections connected by an elbow-joint to produce a self-bracing shell, the fire-box being arranged at the bottom of one rounded section and the fire tubes or flues and the combustion-chamber arranged in the two sections 70 above and in rear of the fire-box, substantially as herein set forth.

4. A boiler made in two cylindrical or rounded sections connected by an elbow-joint to produce a self-bracing shell, the fire-box 75 being arranged at the lower end of one rounded section and the fire tubes or flues and combustion-chamber arranged in the two sections above and in rear of the fire-box, and with a steam-dome on the shell, substantially as herein set forth.

5. The combination, in a boiler, of two cylindrical or rounded sections A B, connected in elbow form, a fire-box F at the bottom of section A, a combustion-chamber H above 85 the fire-box, tubes connecting the fire-box and combustion-chamber, and fire-tubes communicating with the combustion-chamber and with the uptake or back connection of the boiler, substantially as herein set forth. 90

6. The combination, in a boiler, of a shell, a fire-box therein, a combustion-chamber above the fire-box, tubes connecting the fire-box and combustion-chamber, fire-tubes connecting the combustion-chamber and the uptake or back connection of the boiler, and a water-circulation and man-hole tube crossing the combustion-chamber and communicating with the upper and lower parts of the water-space of the boiler, substantially as herein set 100 forth.

7. The combination, in a boiler, of a shell made in two cylindrical or rounded sections connected in elbow form, a fire-box at the bottom of the front section, a combustion-chamber above the fire-box, tubes connecting the fire-box and combustion-chamber, fire-tubes connecting the combustion-chamber and the uptake or back connection of the boiler, and a water-circulation and man-hole tube crossing the combustion-chamber and communicating with the upper and lower parts of the water-space of the boiler, substantially as herein set forth. 110
